UNITED STATES PATENT OFFICE.

ARTHUR ASCH, OF HAMBURG, GERMANY.

FLEXIBLE OCCLUSIVE PESSARY.

1,083,721.

Specification of Letters Patent.

Patented Jan. 6, 1914.

Application filed December 17, 1912. Serial No. 737,181.

To all whom it may concern:

Be it known that I, ARTHUR ASCH, Med. Dr., a subject of the German Emperor, and resident of No. 54 Billhörner Röhrendamm, 5 Hamburg, Germany, have invented certain new and useful Improvements in or Relating to Flexible Occlusive Pessaries, of which the following is a specification.

The invention relates to an occlusive pessary for women, which is not introduced into the mouth of the womb, but is clamped around the neck of the womb and may be worn permanently without causing inconvenience.

15 According to the invention the occlusive pessary consists in a double tube of soft rubber or the like, which embraces the mouth of the womb, while in the jacket formed by the tube a flexible stiffening frame is provided.

20 The pessary rests with its upper edge against the vagina. At its lower end it is provided with a valve cap, the ducts of which are closed by a double acting valve either from the outside or from the inside.

25 The drawings show—by way of example—such a pessary embodying the invention on an enlarged scale.

Figure 1 is a vertical section and Fig. 2 a plan of the complete pessary, while Fig. 30 3 shows the stiffening frame in vertical section and Fig. 4 the same in plan.

The stiffening frame, composed of steel wire, consists in a large ring *m* and a smaller ring *n*, which are connected by stays *p*.

35 Both, the rings *m*, *n*, as well as the stays *p* are totally or partially formed by helical springs, so the whole frame, which has the shape of a truncated cone, is flexible in every direction. In the constructional ex-

40 ample shown in the drawings, the stays *p* are formed in their upper parts, to about one fourth part of their length, of solid wire, while their lower parts extending down to the lower ring *n* are constructed as helical wire springs, so that the frame at its upper end offers sufficient rigidity to the hand, which introduces the pessary into the womb pipe.

45 Radial arms or supports *q*, directed inwardly, are arranged on the stays *p* and carry pressure plates or pads *u*. These radial supports *q* also are preferably made in the form of helical springs. The whole frame is inclosed inside the pads *u* and out- 55 side the stays *p*, by the tube or flexible casing *a*, whose ends meet on the exterior cir-

cumference of the valve-cap *b*. The inner end of tube *a* is securely clamped on valve-cap *b* by means of the ring *n* of the stiffening frame, while the outer end of tube *a* 60 is secured on the valve-cap *b*, by means of special wire-binding. This latter end of tube *a* is hereby drawn over the ring *n* of the stiffening frame, so that the latter is completely inclosed within the double tube. 65 For this purpose the valve-cap *b* is exteriorly provided with two flanges between which the ends of the tube and ring *n* of the stiffening frame, embrace the valve-cap *b*. This cap is centrally apertured for the ac- 70 commodation of the stem of a duplex puppet valve *d*, which passes loosely through the aperture and carries a disk at each end, one of said disks being located on the outer side of the valve cap, while the other disk 75 is located on the inner side of said cap.

The double acting valve *d* closes by means of its two disks, either from the inside or from the outside, according to its position, the ducts *o* in the valve-cap *b* while in its 80 middle position it allows easy access to douches and injections, so that the pessary need not be removed for the purposes of such operations.

The valve *d* as well as the valve-cap *b* 85 may be produced of metal or other suitable material. If metal be employed it is advisable that the valve and valve-cap, as well as the wire frame should be nickel plated or otherwise protected from corro- 90 sion.

What I claim is:—

1. A pessary comprising a flexible tubular casing adapted to embrace the mouth of the womb and rest with its upper end against 95 the vagina, a flexible stiffening frame within the casing, an apertured cap provided with a port and arranged on the lower side of the frame, and a duplex puppet valve having a stem that passes loosely through 100 the apertured cap and carries a disk at each end, one of said disks being located on the outer side of the valve cap, while the other disk is located on the inner side of said cap.

2. A pessary comprising a flexible tubular 105 casing adapted to embrace the mouth of a womb and rest with its upper edge against the vagina, a flexible stiffening frame within the casing, pressure members extending inwardly from the frame and engaging the 110 inner portion of the tubular casing, an apertured cap provided with a port and ar-

ranged on the lower side of the frame, and a duplex puppet valve having a stem that passes loosely through the apertured cap and carries a disk at each end, one of said 5 disks being located on the outer side of the valve cap, while the other disk is located on the inner side of said cap.

Signed by me at Hamburg this fourth day of Dec. 1912.

ARTHUR ASCH.
